UNITED STATES PATENT OFFICE

163,736

ELECTRIC CIRCUIT BREAKER UNIT

Charles Bangert, Jr., New Britain, Conn., assignor
to The Trumbull Electric Manufacturing Com-
pany, Plainville, Conn., a corporation of Con-
necticut

Application February 1, 1951, Serial No. 14,058

Term of patent 14 years

(Cl. D26—13)

To all whom it may concern:

Be it known that I, Charles Bangert, Jr., a citizen
of the United States of America, residing at
New Britain, county of Hartford, and State of
Connecticut, have invented a new, original, and
ornamental Design for an Electric Circuit Breaker
Unit, of which the following is a specification,
reference being had to the accompanying drawing
forming part thereof.

Fig. 1 is a perspective view of an electric circuit
breaker unit, embodying my new design, the
view being from the right hand side, the left
hand side having a similar appearance.

Fig. 2 is a rear view thereof.

Fig. 3 is a bottom view thereof.

I claim:

The ornamental design for an electric circuit
breaker unit, substantially as shown and de-
scribed.

CHARLES BANGERT, JR.
